SLEEVE FOR INSULATED SWITCH RODS

Filed Sept. 19, 1927

2 Sheets-Sheet 2

UNITED STATES PATENT OFFICE.

THOMAS O'BRIEN, OF PHILADELPHIA, PENNSYLVANIA.

SLEEVE FOR INSULATED SWITCH RODS.

Application filed September 19, 1927. Serial No. 220,297.

My invention relates to a new and useful sleeve for switch rods, lock rods, pull rods, and the like, and more particularly to a sleeve construction for switch rods whereby the points or tongues of a single or multiple switch may be "thrown" or actuated to open or close one or more main tracks.

My invention further relates to a sleeve construction for rods of the character stated, whereby the rails of the track or tracks controlled are maintained in perfect electrically insulated relation to each other notwithstanding the actuation of all of said rails by a single common rod.

My invention still further relates to a novel sleeve construction which in addition to insulating the rod actuating the tracks, also affords the requisite stability and ease of motion for the rod and its adjuncts to insure efficiency and accuracy of operation.

To the above ends, my invention consists of an outer metallic sleeve for a switch rod and the like, insulating means intermediate said sleeve and said rod, and an inner protecting sleeve intermediate said insulating means and said rod.

My invention further consists of novel means for securing the sleeve encasing the rod and its adjuncts to the successive, spaced main rails of a track or to the tongues or points of a switch on a track, in such a manner as to guard against slipping or jamming to insure efficient and accurate operation.

My invention further consists in so shaping and constructing the sleeve encasing the rod and its adjuncts as to impart the necessary stability to the switch rod or other construction to prevent the twisting or turning of the sleeve during application.

My invention further consists of novel means for actuating a switch or other rod equipped with the sleeve construction of my invention, comprising a basket rigidly secured to the rod and having an actuating rod or lever extending to the switch machine or other point of actuation whereby the rod is moved transversely of the main rails of a track to open and close a switch or the like.

My invention further consists of various other novel features of construction herein after described and claimed.

For the purpose of illustrating my invention I have shown in the accompanying drawings one form thereof which is at present preferred by me, since the same has been found in practice to give satisfactory and re-

liable results, although it is to be understood that the various instrumentalities of which my invention consists can be variously arranged and organized and that my invention is not limited to the precise arrangement and organization of the instrumentalities as herein shown and described.

In the accompanying drawings:

Fig. 1, represents a top plan view of a double cross over switch rod shown applied to railroad tracks and equipped with the novel sleeve construction embodying my invention.

Fig. 2, represents a similar plan view of a single cross over switch rod applied to railroad tracks, and equipped with the sleeve construction embodying my invention.

Fig. 3, represents a sectional view on line 3—3 of Fig. 1, certain parts being shown in elevation.

Fig. 4, represents a sectional view on line 4—4 of Fig. 3.

Fig. 5, represents a perspective view of the novel sleeve embodying my invention.

Fig. 6, represents a perspective view of the novel clip employed in securing the sleeve encasing the switch rod to the tongue or point of a switch.

Fig. 7, represents a perspective view of the novel hanger washer employed in securing the sleeve encasing the switch rod to the tongues of a switch.

Referring to the drawings, in which similar numerals of reference indicate corresponding parts, 1 designates a continuous, integral switch rod provided at spaced intervals along the length thereof with the screw threaded portions 2, which are adapted to receive and engage the internally threaded locking nuts 3. 4 designates a metallic sleeve or casing through which the rod 1 extends and which is provided with the annular rim or flange 5 at one end thereof and with the square or rectangular portion 6 at the other end thereof, the latter end being also provided with the squared shoulder 7, as will be understood from Fig. 5. 8 designates an inner insulating sleeve made of any suitable material, such as fiber or the like, which forms a lining for the metallic sleeve 4 and electrically insulates the rod 1 to prevent the occurrence of short circuits and the resulting interference with the light signals along the track. A pair of insulating washers 9 abut against the flange 5 and shoulder 7 at the respective ends of the

105

110

sleeve 4 and are held in place by the outer metallic washers 10 and the lock nuts 3 to complete the insulation of the rod 1, as will be understood from Fig. 3. Intermediate the shoulder 7 and the insulating washer 9 and outer metallic washer 10 are interposed the clip 11 and hanger washer 12 which are secured to the switch tongue 13 by the plates 14 and bolts 15. The clip 11 is provided with the enlarged rectangular opening 16 through which projects and in which is adjustably supported the squared end portion 6 of the sleeve 4, as will be understood from Fig. 4. Similarly, the hanger washer 12 is provided with the squared opening 17 through which, also, the square end portion 6 of the sleeve is adapted to project, as will be understood from Fig. 3. Unlike the hanger washer 12, the clip 11 is further provided with the lower opening 18 through which the rod 1 may be dropped after the nuts 3 have been loosened and the sleeve 4 has been withdrawn until the squared end 6 thereof has cleared the clip 11, thus permitting the adjustment or repair of any section of the rod or the disconnection of the same from any switch tongue or point without removing the bolts 15 or disconnecting the clip and its adjuncts, it being understood that the hanger washer 12 is detached from the clip 11 by the loosening of the nuts 3. A basket 19, rigidly connected to the switch rod 1 at any suitable point along the length thereof, is provided with the lever or rod 20 extending to the switch machine (not shown) whereby the switch may be "thrown" to close or open a track, as will be understood from Figs. 1 and 2.

22 designates an inner metallic sleeve interposed between the rod 1 and the insulating sleeve 8 to prevent the rapid wearing out of the latter, which would otherwise result from constant contact with the screw threads on the rods. The metallic sleeve 22 further serves to reduce the friction between the rod 1 and the insulating sleeve 8, which is usually made of fiber or the like, particularly when said insulating sleeve 8 is wet.

50 My present invention is an improvement over my prior Patent No. 986,307, dated March 7, 1911, an important feature of the present invention being the provision of the squared opening in the clip 11 and the hanger washer 12 which receive and engage the correspondingly squared end 6 and shoulder 7 on the end of the sleeve 4, to prevent the turning or twisting of the sleeve while the switch is opened or closed, and at the 55 same time to permit of a certain amount of play or lateral adjustment to guard against the jamming of parts.

While I have described my novel sleeve attachment in connection with a switch rod, it is to be understood that this construction

is equally applicable to lock rods, pull rods, and the like, and that my invention is not limited to the switch rod construction herein shown and described.

It will now be apparent that I have devised a novel and useful construction which embodies the features of advantage enumerated as desirable in the statement of the invention and the above description, and while I have in the present instance shown 70 and described the preferred embodiment thereof which has been found in practice to give satisfactory and reliable results, it is to be understood that the same is susceptible of modification in various particulars so without departing from the spirit or scope of the invention or sacrificing any of its advantages.

Having thus described my invention, what I claim as new, and desire to secure by Letters Patent, is:

1. A sleeve for switch rods having one end polygonal and provided with a polygonal shoulder and means for securing said sleeve to a switch tongue comprising a clip 90 having a lower member abutting against said polygonal shoulder and having a polygonal opening therein for receiving said polygonal end, and a hanger washer having a lower member abutting against said clip 95 and having a polygonal opening therein for receiving said polygonal end.

2. A cylindrical sleeve for switch rods having one end squared and provided with a squared shoulder, means for securing said sleeve to a switch tongue comprising a clip having a lower member abutting against said squared shoulder and having a rectangular opening therein for receiving said squared end, and a hanger washer having a lower member abutting against said clip and having a squared opening therein for receiving said squared end, there being an opening in the lowermost edge of said clip communicating with said rectangular opening.

3. In a device of the character stated, a rod having screw threaded sections and adapted to actuate a switch tongue, a metallic sleeve encasing said rod and having one end squared and provided with a squared shoulder, means for securing said sleeve to said rod including a clip having a lower member adapted to abut against said squared shoulder and having a rectangular opening therein, a hanger washer abutting said clip and having a squared opening therein, lock nuts engaging said screw threaded sections, means for securing the upper end of said clip to a switch, and means for electrically insulating said rod.

4. In a device of the character stated, a rod having screw threaded sections and adapted to actuate a switch tongue, an outer, metallic sleeve encasing said rod and having one end thereof squared and provided

with a squared shoulder, means for securing said sleeve to said rod including a clip having a lower member adapted to abut against said squared shoulder and having a rectangular opening therein, a hanger washer abutting said clip and having a squared opening therein, lock nuts engaging said screw threaded sections, means for securing the upper end of said clip to a switch tongue, means for electrically insulating said rod in-

cluding an insulating sleeve and insulating washers, and an inner metallic sleeve intermediate said rod and said insulating sleeve, there being an opening in the lower end of said clip communicating with said rectangular opening. 15

In testimony whereof, I have hereunto signed by name.

THOMAS O'BRIEN.
